United States Patent Office

Des. 208,538
Patented Sept. 12, 1967

208,538

CONCRETE PLACER

Salvatore F. Aiello, Racine, Wis., assignor to J. I. Case
Company, Racine, Wis., a corporation of Wisconsin

Filed Sept. 15, 1966, Ser. No. 3,875

Term of patent 7 years

(Cl. D14—3)

Des. 208,538

PAGE 2

FIG. 3

FIG. 4

FIG. 6

FIG. 2 is a perspective view taken from the right and rear side of the placer shown in FIG. 1;

FIG. 3 is a plan view of the placer shown in FIGS. 1 and 2;

FIG. 4 is a left side view of the placer;

FIG. 5 is a front view of the placer; and

FIG. 6 is a rear view of the placer.

The dominant features of the design reside in the portions shown in full lines.

I claim:

The ornamental design for a concrete placer, substantially as shown and described.
